UNITED STATES PATENT OFFICE.

FREDERICK H. SLOAN, OF HARTFORD, CONNECTICUT.

DESIGN FOR A HANDLE FOR SPOONS, &c.

SPECIFICATION forming part of Design No. 20,625, dated March 24, 1891.

Application filed January 22, 1891. Serial No. 378,702. Term of patent 7 years.

To all whom it may concern:

Be it known that I, FREDERICK H. SLOAN, a citizen of the United States, residing at Hartford, in the county of Hartford and State of Connecticut, have invented and produced a new and original Design for Spoons, Forks, and the Like, of which the following is a specification, reference being had to the accompanying drawing, forming a part thereof.

10 The figure is a plan view of the design for a spoon, this view illustrating my design.

The invention relates to the ornamentation of the handles of spoons, forks, and the like household articles of all sizes and classes; and 15 the object is to provide an ornamental and aesthetic pattern for the handles of such articles, which will give them a unique, characteristic, and historic appearance.

The leading feature of my design resides 20 in a representation of an old oak-tree having a large trunk, in which is an opening, with wide-spreading branches provided with foliage, the contour of which very nearly conforms to the outline of the gradually widening or

swelling end of the handle of the article, upon which it is so placed as to produce the appearance of bas-relief, in order to create a realistic impression of an old tree. Below the tree is arranged a number of characters or letters so associated as to produce a chain-like appearance upon the slender stem of the handle.

The letter *a* indicates the widened portion of the handle of a spoon, and *b* an old oak-tree, with an opening or hollow *b'* represented in the trunk.

Below the tree and dropping down upon the stem of the handle is a raised ornamental lettering *d*, intertwined to produce a chain-like appearance upon the surface of the stem.

What I claim is—

The design for the handles of spoons, forks, or the like household articles herein shown and described.

FREDERICK H. SLOAN.
